(57) **CLAIM**

We claim the ornamental design for a rearview mirror device, as shown and described.

DESCRIPTION

FIG. 1 is a front perspective view of a rearview mirror device of the present disclosure;

FIG. 2 is a rear perspective view of the rearview mirror device of FIG. 1;

FIG. 3 is a front elevational view of the rearview mirror device of FIG. 1;

FIG. 4 is a rear elevational view of the rearview mirror device of FIG. 1;

FIG. 5 is a side elevational view of the rearview mirror device of FIG. 1;

FIG. 6 is a top plan view of the rearview mirror device of FIG. 1; and,

FIG. 7 is a bottom plan view of the rearview mirror device of FIG. 1.

The broken lines depict portions of the rearview mirror device in which the design is embodied that are not considered part of the claimed design.
